CLAIM

The ornamental design for a wall mount for a monitoring camera, as shown and described.

DESCRIPTION

FIG. 1 is a top, front, right-side perspective view of a wall mount for a monitoring camera showing our new design; FIG. 2 is a top, rear, left-side perspective view thereof; FIG. 3 is a bottom plan view thereof; FIG. 4 is a top plan view thereof.

FIG. 5 is a left side elevation view thereof;

FIG. 6 is a right side elevation view thereof;

FIG. 7 is a rear elevation view thereof; and,

FIG. 8 is a front elevation view thereof.

The broken lines in the drawing views are included to illustrate environment only and form no part of the claimed design.
